UNITED STATES PATENT OFFICE

HENRY C. SERGEANT, OF NEW YORK, N. Y.

ROCK-DRILL.

SPECIFICATION forming part of Letters Patent No. 326,597, dated September 22, 1885.

Application filed October 13, 1884. (No model.)

To all whom it may concern:

Be it known that I, HENRY C. SERGEANT, of the city and county of New York, in the State of New York, have invented a new and useful Improvement in Rock-Drills and other Engines, of which the following is a specification.

My invention relates in part to the devices employed for cushioning the blow of the piston upon either cylinder-head of a rock drill, whereby greater simplicity, durability, and efficiency are secured than in rock-drills heretofore used.

The invention also relates to a novel construction and combination of parts for rotating the piston, piston-rod, and drill, as hereinafter described, whereby simplicity of construction and certainty of operation are secured.

The invention also relates to a valve of novel construction for controlling the admission of actuating fluid to the drill-cylinder, and which is also applicable to other engines or machines, especially those wherein are employed a reciprocating piston working in a cylinder, such as chipping-machines, riveting-machines, and hammers operated by steam or air.

In the accompanying drawings, Figure 1 is a vertical section of a drill embodying my invention, showing it adapted and adjusted for drilling holes at a slight inclination to the perpendicular. Fig. 2 is a front elevation of the drill. Fig. 3 is a sectional view of a portion of the cylinder, and an exterior view of the piston, piston extension, and rotating devices. Fig. 3* is a sectional view on the line xx , Fig. 3. Fig. 4 is a side view of the drill lying nearly horizontal. Fig. 5 is a sectional view on the line **, Fig. 2. Fig. 6 is a horizontal section on the line yy , Fig. 1. Fig. 7 is a sectional view of a portion of a drill embodying a modification of my invention. Fig. 8 is a sectional view similar to Fig. 6, but on a larger scale, of my improved valve and such parts of the drill-cylinder as are necessary to illustrate this part of the invention, and Fig. 9 is an end view of the valve.

Similar letters of reference designate corresponding parts in all the figures.

A designates a strong but light frame, which may be made of cast metal, and which in some respects is similar to the ordinary drill-back—that is to say, the drill-cylinder B is adjusta-

ble therein to feed the drill forward to the work. The back or frame A is slotted longitudinally at A*, and the sides of the slot form parallel guides a, to which are fitted gibbed slides b at the back of the cylinder B.

The feed-screw C is fitted to a bearing, c, in the top of the frame A, whereby its lengthwise movement is prevented, and engages a nut, b*, in one of the slides b. On the screw C is a crank or handle, C', and by turning the screw the cylinder may be moved in the back or frame A in a well-known manner.

The back or frame A is broadened near the lower end, and comprises sockets d, in which are fitted points or centers e, which bear on the rock and form two of the three bearing points or feet of a tripod-support. The points or centers e are secured in place by set-screws e', which have, or may have, pointed or conical heads, as shown best in Fig. 5, and for a purpose hereinafter described. The third foot or bearing-point of the tripod-support is furnished by a back brace or leg, which is pivoted to the drill-back A by means of a bolt, f, which passes through an eye in the head g of the brace, and through lugs or ears f' on the back or frame A. The leg or back-brace may be set at any angle desired, and may be there clamped by a hand-nut, f'', as best shown in Fig. 6. The back-brace is extensible, or capable of elongation and contraction, and, as here shown, consists of an upper tubular section, D, and a lower section, D', sliding telescopically in the upper section, and secured in any desired relation thereto by means of a collar or band, D'', sliding upon the exterior of the tubular brace-section D, and provided with a set-screw, h, the point of which passes through a slot, *, in the tubular section D. The point of the screw h enters a slight depression in the extensible section D' of the brace, and hence the band or collar D'' is caused to slide along the exterior of the tubular section as the section D' slides in the interior thereof. When the screw h is tightened, it forces the extensible section D' tightly against the inner side of the tubular section D and draws the band or collar D'' tightly against the exterior of the tubular section D.

The three legs or bearing-points form an adequate support for the machine, and if when using a motive agent of very high press

J, and hence acts as a nut to turn the piston and drill.

The piston-extension in both examples of my invention has more spiral grooves n^6 than are necessary for the engagement of the lugs on the ring J*, four grooves being here shown. The grooves which are not engaged by the nut serve for the passage of steam or motive fluid to act upon the end of the piston or piston-extension.

What I claim as my invention, and desire to secure by Letters Patent, is—

1. The combination, with the cylinder, piston, and cylinder-head of a rock-drill, of a spring for holding the head in place with a yielding pressure, consisting of a steel plate bent or deflected between its ends and having a bearing against the outer side of the head, substantially as herein described.
2. The combination, with the cylinder, piston, and cylinder-heads of a rock-drill, of bolts connecting the said heads, and a spring interposed between the upper head and the bolts, and consisting of a steel plate bent or deflected between its ends and bearing on the upper head, substantially as herein described.
3. The combination, with the cylinder and heads B B' B'', and bolts H, connecting the heads and provided with nuts, of the spring I, consisting of a bent steel plate having a bearing on the head B', and having ears or lugs m, which receive said bolts, substantially as herein described.
4. The combination, with the cylinder of a rock-drill and a piston and spirally-grooved piston-extension, of two rings provided with ratchet-teeth on their adjacent faces and receiving the piston-extension through them, one of said rings being secured in the cylinder, and the other being engaged with the spiral grooves of the piston-extension, and a spring supporting the last-mentioned ring and holding it in engagement with the ring secured in the cylinder, substantially as herein described.
5. The combination, with the cylinder, piston, and spirally-grooved piston-extension of a rock-drill, of two rings receiving the piston-extension through them and provided with ratchet-teeth on their adjacent faces, one ring being secured in the cylinder and the other being engaged with the spiral grooves of the piston-extension, and a spring, n^4 , consisting of a steel ring deflected at points in its circumference and holding the rings in engagement, substantially as herein described.

6. The combination, with the cylinder, piston, and spirally-grooved piston-extension of a rock-drill, of two rings receiving the piston-extension through them and provided with ratchet-teeth on their adjacent faces, one of said rings being held by friction against turning in the cylinder and the other being engaged with the spiral grooves of the piston-extension, and a spring for holding the last-mentioned ring in engagement with the other ring, substantially as herein described.

7. The combination, with the cylinder, piston, the spirally-grooved piston-extension, and the cylinder-heads of a rock-drill, of the rings J J*, provided with ratchet-teeth on their adjacent faces, the ring J being clamped between the lower head and a shoulder in the cylinder, a spring for supporting the ring J*, bolts connecting the heads, and a cushioning spring serving to hold the heads in place and to clamp the ring J and hold it by friction against turning, substantially as herein described.

8. The combination, with the cylinder B, having the shoulder n^3 , the piston and piston-extension, and the lower head, B', with the projecting ring or bush n' , of the ratchet-toothed rings J J*, the former having a flange, n^2 , whereby it is clamped between the shoulder n^3 and the ring or bush n' , all substantially as herein described.

9. The combination, with the cylinder and piston, the cylinder having an intermediate exhaust port or passage across which the piston travels, and a valve-casing provided at opposite ends with seats, and ports leading therefrom to the cylinder, of a valve consisting of a skeleton structure having heads or disks which are adapted to close against said seats, the heads or disks of the valve being larger in diameter than the seats, so that when seated a portion of the end of the valve around the seat will be exposed to pressure, and having in them holes or notches radially beyond the seats, substantially as herein described.

10. The combination, with the valve-casing K, provided with seats $p p'$, and ports leading therefrom, of the valve K', having heads or disks $r r'$, larger in diameter than said seats, and provided with notches or holes r^* , substantially as herein described.

H. C. SERGEANT.
